CLAIM

The ornamental design for a headboard for a bed, as shown and described.

DESCRIPTION

FIG. 1 is a perspective view of a headboard for a bed showing my new design;

FIG. 2 is a side elevational view, the opposite side being a mirror image thereof;

FIG. 3 is a top plan view;

FIG. 4 is a front elevational view; and,

FIG. 5 is a cross-sectional view taken along lines 5—5 of FIG. 4.

The rear of the headboard is plain and unadorned.
